A. CHAMPION

SPARK PLUG

Filed March 8, 1920

UNITED STATES PATENT OFFICE.

ALBERT CHAMPION, OF FLINT, MICHIGAN, ASSIGNOR TO A C SPARK PLUG COMPANY, OF FLINT, MICHIGAN, A CORPORATION OF MICHIGAN.

SPARK PLUG.

Application filed March 8, 1920. Serial No. 364,015.

To all whom it may concern:

Be it known that I, ALBERT CHAMPION, a citizen of the United States, and a resident of Flint, county of Genesee and State of Michigan, have invented certain new and useful Improvements in Spark Plugs, of which the following is a full, clear, concise, and exact description, such as will enable others skilled in the art to which the invention relates to make and use the same, reference being made therein to the accompanying drawings, which form a part of this specification.

My invention relates to spark plugs of the general class or type wherein a series of sparks are caused to pass between an outer electrode which is supported by the hollow metallic shell or casing of the plug, and an inner electrode which extends through an insulating member secured in place within said outer shell or casing; and particularly to certain features associated with the outer of the said electrodes, that is the one which is carried by and projects from the inner end of the external hollow metallic shell or casing of the plug.

The principal object of my invention is to provide an improved form, construction, and arrangement of the outer electrode of a spark plug of the general class or type above referred to and by the use of which improvements a more rigid and a stronger outer electrode is secured; and at the same time to provide a plug in which the life thereof is prolonged, because of a distribution of the sparks which are produced when the plug is in use throughout a greater portion of the extremities of the inner and of the fixed outer electrodes than has heretofore commonly been the case.

With the above and other objects of invention in view, my invention consists in the improved fixed or outer electrode construction and arrangement illustrated in the accompanying drawing and hereinafter described and claimed; and in such variations and modifications thereof, within the scope of the concluding claims, as will be obvious to those skilled in the art to which my invention relates.

Referring now to the drawing accompanying and forming a part of this specification and wherein the preferred embodiment of my invention is illustrated:

Figure 1 is a view showing a common

form of spark plug equipped with one form of my improved electrode, the view being partly in section and partly in side elevation.

Figure 2 is a sectional view showing the inner end of the spark plug shown in Figure 1 upon a larger scale, the outer electrode being somewhat modified as to certain of its features.

Figure 3 is a view similar to Figures 1 and 2, but showing a slightly different form of my invention.

Figure 4 is a view showing the inner end of a plug having an electrode made in accordance with my invention, and in which the same differs somewhat from the form shown in the other figures.

Figure 5 is a fragmentary view illustrating the form of electrode shown in Figure 2 upon a larger scale, and in perspective, to show the arrangement of the base thereof relative to the portion of the outer casing from which it projects.

Figures 6 to 10, inclusive, are fragmentary views illustrating various modifications of my improved outer electrode, particularly as regards the form or shape of the free end thereof.

Referring now to the drawing, the reference numeral 10 designates the external hollow metallic shell or casing of a spark plug of common and well known form, and within which an insulating member 11 is secured in any of the ways at present employed in securing insulating members in place within such shells or casings; while the reference numeral 12 designates the inner electrode of the plug, the same being supported in a central position within a passage formed in and extending longitudinally of the said insulating member.

Carried by and extending from the inner end of the metallic shell or casing 10 is an outer electrode designated by the reference numeral 13, one end of which is welded or otherwise secured to the end of the said shell or casing. This outer electrode is oblong, or substantially rectangular, in cross section, and the inner end or base thereof is secured to the inner end of the shell or casing in any way, as by welding the same to said inner end as above stated and in accordance with the patent to A. Schmidt, No. 1,319,423, October 21, 1919. The arrangement of the said outer electrode is shown as

such that its base portion where it is welded to the free end of the shell or casing has its longer dimension extending circumferentially of the said inner end; so that the greatest dimension of the joint between said electrode and the surface of the shell from which it projects extends at right angles to the diameter of said shell.

The free end of the outer electrode 13, to which the reference numeral 14 is applied, is bent over toward the central electrode at substantially a right angle to the body portion of said outer electrode, and the length of said bent over portion is such that its extremity lies adjacent the central electrode 12 of the finished plug, so that sparks may pass between the electrodes when the plug is in use.

Various of the advantages of my invention will be secured by the use of an outer electrode extending from the inner end of the shell or casing of the plug and the end of which is bent over so as to lie adjacent the inner electrode and the cross section of which outer electrode is substantially rectangular, as above pointed out. I prefer, however, to twist the bent over portion 14 of the said outer electrode throughout an angle of substantially ninety degrees, so as to cause the extremity thereof to extend substantially parallel with the end portion of the central electrode adjacent which it lies. Such a construction and arrangement of the outer electrode results in a distribution of the sparks which pass between the extremities of the electrodes throughout a much greater area than would be the case if the outer electrode was circular in cross section; thus distributing the wear due to the passage of the sparks between the two electrodes throughout a much greater area than would otherwise be the case and prolonging the life of the plug.

The extremity of the outer electrode may if desired be provided with a plurality of sparking points or teeth, as indicated by the reference numerals 15, which construction provides a plurality of points between which the spark pass and a plug in which the sparks passing between the central electrode and the outer electrode will pass between various points of said electrodes; each spark occurring between the central electrode and some one point of the outer electrode, the particular points between which the spark passes being determined in the case of each discharge by the resistance of the path along which the current flows. It therefore follows that as soon as the resistance of the path along which sparks are assumed to be passing becomes greater than the resistance of another path the sparks will cease to pass between the first assumed points, and will pass between another point of the outer electrode and the central elec-

trode; thus distributing the wear due to the passage of the sparks between all the points upon the outer electrode, or along the entire length thereof if the extremity of said electrode is not provided with distinct teeth and providing an electrode structure in which the life of the outer electrode is very much increased.

It will furthermore be appreciated that my invention provides an electrode of uniform cross section throughout, and one which may be formed from wire of oblong or rectangular cross section as hereinbefore explained; and which electrode when twisted so as to provide a sparking edge extending parallel with the inner electrode results in a plug in which the sparks are distributed throughout a much greater area than would otherwise ordinarily be the case; such end being attained, as will be appreciated, without imparting any special shape to the extremity of the outer electrode as the distribution of the sparks throughout the entire area thereof will occur even if the toothed construction at the end be not employed. At the same time the outer electrode is of greater strength because of the form of the wire employed in the formation thereof and the arrangement of the welded joint between its fixed end and the end of the external shell or casing; and the twisting of the same intermediate its length provides an extremely rigid form of electrode and one in which the change in angular position between the two parts thereof at the right angle at which the twist occurs imparts increased strength and rigidity to the electrode at the bend thereof, which has heretofore been a weak point in spark plug electrodes of the right angular type, that is of the type wherein the free end of the electrode is bent over at a right angle to the body portion thereof to cause its extremity to lie close to the central electrode of the plug.

The use of wire oblong in cross section in the formation of the outer electrode in addition to providing strength and rigidity therein provides an electrode of increased mass through which a free flow of heat may occur from the spark gap where heat is produced by the passage of the sparks along and through said electrode and to the external casing of the plug, and from there to the engine, thus providing for the conduction of the heat produced at the spark gap away therefrom more effectively than would be the case if an electrode of less cross sectional area was employed and maintaining a comparatively low temperature at the spark gap, while at the same time retaining the advantages of an outer electrode separate from the shell or casing of the plug and projecting from the inner end thereof.

The advantages of enhanced strength and stiffness and of increased mass for provid-

ing a more free flow of heat from the sparking points inherent in an outer electrode which is oblong in cross section as disclosed herein are secured irrespective of the form 5 of the extremity thereof at which the sparks pass from said electrode to the inner electrode; from which it follows that the extremity of the said outer electrode may be variously shaped without departing from 10 my invention regarded in its broader aspect, and as comprehending an outer electrode which is oblong in cross section. Thus in the form of my invention illustrated in Figure 1 the extremity of the stationary electrode is straight, while in Figures 2, 3, 15 4 and 5 it is serrated, a distribution of the sparks throughout the area of the extremity being however secured in both cases; while in the form illustrated in Figure 6 there 20 are two surfaces 16 arranged at about a right angle to one another and in between which surfaces the inner electrode 17 is located, thus securing a distribution of the sparks between the central electrode and 25 the two surfaces in question.

In the form of electrode illustrated in Figures 7 and 8 the end of the electrode is tapered, as indicated at 18 and 19, thus reducing the area at the extremity thereof 30 as is permissible in the case of an electrode made from an alloy which wears away slowly at the sparking points without, however, reducing the strength or stiffness of the electrode as a whole which is imparted to 35 it by its oblong cross sectional area; and without reducing the efficiency thereof as regards the conduction of heat away from the sparking point and to the shell of the plug; while Figure 9 shows a form of electrode in which the end 20 thereof is widened, thus providing an edge of greater length than the width of the electrode and a more extended surface along or over which the 40 sparks may be distributed as hereinbefore explained; such edge being either serrated as shown, or smooth if such form is deemed desirable.

Figure 10 shows a form of my invention in which the outer electrode 21 while still 45 oblong in cross section is secured in place to the outer shell 22 of the plug with its longer dimension radial, relative to the central electrode; the base of the said outer electrode being either welded to the flat end 50 of the shell or secured in place by welding or otherwise in a radially extending groove provided in the end of the shell for the reception of such base portion of the electrode.

Having thus described and explained my invention, I claim and desire to secure by Letters Patent:

1. In a spark plug of the class described, an external hollow metallic shell or casing; an outer electrode oblong in cross section

carried by said shell and projecting from the inner end thereof, and the arrangement of which electrode is such that its longer dimension extends circumferentially of the end of said shell or casing; and a central 70 electrode supported by an insulating member secured in place within said shell; the free end of said outer electrode being bent substantially at right angles to the fixed portion thereof, and twisted through an angle of substantially ninety degrees, and the extremity of which outer electrode extends substantially parallel with and lies adjacent the said central electrode and is provided with a plurality of sparking points 80 or teeth.

2. In a spark plug of the class described, an external hollow metallic shell or casing; an outer electrode oblong in cross section carried by said shell and projecting from the inner end thereof, and the arrangement of which electrode is such that its longer dimension extends circumferentially of said shell or casing; and a central electrode supported by an insulating member secured in 85 place within said shell; the free end of said outer electrode being bent substantially at right angles to the fixed portion thereof, and twisted through an angle of substantially ninety degrees, and the extremity of which outer electrode extends substantially parallel with and lies adjacent the said central electrode.

3. In a spark plug of the class described, an external hollow metallic shell or casing; an outer electrode oblong in cross section carried by said shell and projecting from the inner end thereof, and the arrangement of which electrode is such that its longer dimension extends circumferentially of the end of said shell or casing; and a central electrode supported by an insulating member secured in place within said shell; the free end of said outer electrode being bent substantially at right angles to the fixed portion thereof, and the extremity of said outer electrode lying adjacent said central electrode and being provided with a plurality of 100 105 110 115 120 125

sparking points or teeth.

4. In a spark plug of the class described, an external hollow shell or casing; an outer electrode oblong in cross section carried by said shell and projecting from the inner end thereof; and a central electrode supported by an insulating member secured in place within said shell; the free end of said outer electrode being bent substantially at right angles to the fixed portion thereof, and twisted through an angle of substantially ninety degrees, and the extremity of which outer electrode extends substantially parallel with and lies adjacent said central electrode.

In testimony whereof I affix my signature.

ALBERT CHAMPION,
